UNITED STATES PATENT OFFICE.

FRANK REINOSKY, OF BEAVER, TERRITORY OF ALASKA.

FLOOR FOR BABY CRIBS.

Application filed November 3, 1924. Serial No. 747,439.

This invention pertains to an improvement in a floor bottom for baby cribs and it is an object of my invention to provide a readily removable and detachable floor or bottom of this character containing certain improvements and advantages which will readily appear from a description of the accompanying drawings.

Figure 1 is an elevational view of a conventional type of baby crib for the purpose of illustrating my invention;

Figure 2 is a sectional view of a bottom and removable floor section of a baby crib with a portion broken away, embodying one form of my invention; and

Figure 3 is a top plan view of the bottom and removable floor shown in Figure 2.

It will, of course, be understood that my improved bottom and floor may be embodied in, and as a part of any suitable and well known baby crib, in other words, the super-structure therefor may be of any desirable or suitable form.

Referring to the drawings in detail, and having in mind the particular embodiment shown, 10 indicates the bottom frame work of the crib, which is rectangular in shape, having sides and ends and is provided with an inner supporting ledge 11 extending around the sides and ends. Supported on and adapted to fit tightly within this annular ledge is a liquid-proof pan 12 constructed of rubber or other suitable material. Detachably mounted within the pan 12, and adapted to fit tightly within is a readily removable false floor 13 constructed of wood or similar material of substantial thickness, which member is of sufficient size to tightly wedge the up-standing flanges or edges 14 of the pan 12 tightly against the shoulder 15 of the bottom frame-work 10. The false bottom or floor 13 is provided with a plurality of openings 16, so that any liquid in the crib may percolate or flow down through these openings into the pan. The super-structure of the crib may be secured to the bottom in any well known manner, for example, by inserting the rungs 18 in suitable openings in the bottom frame-work, as best shown in Figure 2.

With my improved invention it will be

seen that I have provided an arrangement which makes for a dry bed and, at the same time the bottom can be readily removed and cleaned and the pan emptied.

Having thus described my invention, I claim:

1. As an article of manufacture, a portable crib for infants comprising in combination a bottom frame member provided with vertical and horizontal supporting shoulders, a flexible liquid proof member supported on and within said shoulders having upwardly extending flanges engaging the vertical shoulders and a readily detachable and perforated rigid false bottom of substantial thickness positioned within said liquid-proof member and supported on said frame member and adapted to tightly clamp the flanges of said liquid-proof member tightly against the vertical shoulders on said frame member, 70 said false bottom and liquid-proof member providing a tightly compact, substantially rigid structure substantially as and for the purpose set forth.

2. A crib construction comprising in combination, a bottom frame member with vertical and horizontal supporting shoulders, a flexible liquid-proof pan supported on and within said shoulders, said pan having upwardly extending flanges engaging the vertical shoulders, and a readily removable false floor adapted to be positioned in said pan and provided with perforations for draining any liquid into the bottom of the pan, said floor fitting into said pan to tightly clamp the upwardly extending flanges of said pan against the vertical shoulders of said member, said combined member, pan and floor providing a rigid, compact, liquid-proof construction, which may be lifted out and dis-assembled by a straight longitudinal pull on said floor, and a super-structure for said crib and attached to said frame member, said frame member providing a base and support for the super-structure.

In witness whereof, I have hereunto subscribed my name at Auburn, Wash., this 18th day of October, 1924.

FRANK REINOSKY.
